UNITED STATES PATENT OFFICE.

KRAFT BOOTH, OF PHILADELPHIA, PENNSYLVANIA, ASSIGNOR TO GILLINDER & SONS, INC., A CORPORATION OF PENNSYLVANIA.

DESIGN FOR A GLASS DOME FOR CEILING-LIGHTS.

45,041.

Specification for Design.

Patented Dec. 16, 1913.

Application filed August 8, 1913. Serial No. 783,824. Term of patent 7 years.

To all whom it may concern:

Be it known that I, KRAFT BOOTH, a citizen of the United States, residing in the city and county of Philadelphia, State of Pennsylvania, have invented a new, original, and ornamental Design for a Glass Dome for a Ceiling-Light, of which the following is a specification, reference being had to the accompanying drawing, forming part thereof.

Figure 1 is a perspective view of a glass

dome for a ceiling light showing my new design. Fig. 2 is a bottom plan view thereof. Fig. 3 is a top plan view thereof.

I claim:—

The ornamental design for a glass dome for a ceiling light, as shown.

KRAFT BOOTH.
